UNITED STATES PATENT OFFICE.

RICHARD D. GALLAGHER, JR., OF NEW YORK, N. Y., ASSIGNOR TO STANDARD COUPLER COMPANY, OF NEW YORK, N. Y., A CORPORATION OF NEW JERSEY.

DRAFT AND BUFFING RIGGING FOR RAILWAY-CARS.

No. 888,008.

Specification of Letters Patent.

Patented May 19, 1908.

Application filed November 22, 1902. Serial No. 182,482.

To all whom it may concern:

Be it known that I, RICHARD D. GALLAGHER, Jr., of New York, in the county of New York, State of New York, have invented certain new and useful Improvements in Draft and Buffing Rigging for Railway-Cars; and I do hereby declare the following to be a full, clear, and exact description of the same, reference being had to the accompanying drawings, forming a part of this specification, and to the figures and letters of reference marked thereon.

This invention relates to improvements in draft and buffing rigging for railway cars, although, as will herein after appear, features of the invention are applicable in any mechanism employed for the purpose of yieldingly resisting the relative movement of parts.

20 The object of the invention is to provide a structure having elasticity so modified by friction that the elastic resistance to compressive strains is vastly augmented and the recoil reduced to a minimum, which structure shall be self contained and the friction created by the direct action of the elastic member or members, whereby the employment of separate elastic and friction members is avoided.

30 With the above objects in view, the invention consists in an elastic member for the purposes indicated, embodying independent elements elastic in a plane transverse of the line of pressure and having friction faces arranged at an angle both to the plane of elasticity and to the line of pressure, whereby upon the application of pressure, the elements will through the action of the inclined friction faces be put under stress transversely of the line of pressure, the friction upon the inclined faces augmenting the resistance of the elastic elements to movement in one direction and resisting the movement of the elastic elements in the opposite direction to 45 reduce the recoil.

The invention further consists in certain novel details of construction and combinations and arrangements of parts all as will be now described and pointed out particularly 50 in the appended claims.

Referring to the accompanying drawings— Figure 1 is a plan view with the yielding member in half section. Fig. 2 is a transverse section of the structure shown in Fig. 1. 55 Fig. 3 is an elevation partly in section of a

yielding member with the sets of yielding elements both of T-shape in cross section. Figs. 4 and 5 are sectional elevations showing modifications in the form and manner of assembling the elements. Fig. 6 is a transverse section of the structure shown in Fig. 5. Figs. 7, 8 and 9 are views showing further modifications in the form and manner of assembling the elements of the yielding member.

Like letters of reference in the several figures indicate the same parts.

In the application of the invention to draft and buffing rigging for railway cars, ordinary appliances are employed for transmitting the draft and buffing strains thereto, such for instance as the draw bar and tail strap A and B of the accompanying drawings and for which any other preferred devices may be substituted.

75 The pressure resisting member itself may be held between stops of usual character located on the draft timbers as illustrated conventionally at C in the said drawings, the said pressure resisting member being thus substituted in the position of the usual draft and buffing springs. This pressure resisting member embodies in its construction an element or elements elastic in a plane transverse to the line of draft or buffing pressure, the preferred form of element being a split ring or series of split rings, having inclines through which the draft or buffing pressure acts to put the ring under elastic stress by expanding or contracting the same as will 80 hereinafter appear.

85 Referring to Figs. 1 and 2 of the drawings, the resilient friction elements are the split rings D and E which alternate with each other and have inclined contacting faces d, e; 90 which when draft or buffing pressure is applied, slide upon each other creating friction and putting the rings under elastic stress. The rings D are expanded, while the rings E are contracted, but obviously either, but not 95 both may be solid or not split, as will be hereinafter explained, in which case the entire movement of expansion or contraction would take place in the split ring set. A considerable number of rings are preferably 100 employed in order to secure a wide range of movement without straining the metal beyond its elastic limit and to still further increase the power and range of movement, the split rings may be associated with or 110

dinary springs in various combinations, the latter operating to supplement the resistance of the split rings or to secure a preliminary light spring resistance. In Fig. 1 of the drawings a central spring F supplements the resistance of the split rings and also supplements the resistance of a spring G arranged in alinement with the split rings and usually of such strength as to compress to a greater or less degree in advance of the movement of the rings upon each other.

The rings and springs constituting resilient elements of the member are preferably held between heads or followers H, a central bolt I serving to retain the parts in proper assembled position. The ends of the bolt may seat in recesses formed in central bosses or projections H' of the heads or followers, said bosses also serving as a means for properly 20 positioning and centering the springs and rings.

Where rings and springs are arranged in alinement, it is preferred to employ a partition or spacer between them, which may take 25 the form of a simple plate or disk, but is preferably formed to support a casing which will inclose the working parts, thus in said Fig. 1 the spacer is indicated at K and the casing at K', K'', the port K' being integral with the 30 spacer, while the port K'' is in the form of a pair of split cylinders which closely surround the rings D and are expanded by the expansion of said rings. This portion of the casing acts as a resilient element and supplements 35 the resistance of the rings, the friction between the contacting faces of the split cylinder casing and between the casing and rings being an important factor in resisting movement in one direction and reducing recoil 40 when the pressure is relieved.

The cross sectional shape of the rings may be greatly modified to secure strength or elasticity and to present the most efficient resistance to strains of expansion or contraction, thus the rings which are expanded 45 as D, Fig. 1, may be of general T-shape in cross section, while the rings E which are compressed may be of more or less circular section. When this formation is employed, 50 the friction faces d are preferably on the shank or outer portions of the rings D and the friction faces are inclined considerably to the line of draft or buffing pressure, this incline or angle, however, depends upon the 55 character of the material and the pressures the structure is designed to resist. It may be varied as found necessary or desirable, care, however, being taken that it does not go beyond the angle of repose, as in such 60 event pressure would not move the parts to put the rings under stress in the sense in which that term is used herein.

In the preferred construction the head H which co-operates with the rings together 65 with the spacer are formed with annular pro-

jections h k respectively having inclined faces corresponding to the faces d e whereby any tendency to cant or distort the rings is avoided.

In Figs. 3 and 4 the rings D' and E' are 70 shown as both of general T-shape in cross section, the casing being entirely omitted in Fig. 3 and only covering the spring G' in Fig. 4. The heads or followers H' in Fig. 3 co-operate directly with the rings and are 75 formed with annular inclines h' for co-operation with the annular inclines or friction faces of the rings.

The structure illustrated in Figs. 5 and 6 corresponds closely to that shown in Figs. 1 80 and 2 save that the entire casing K' is integral with the spacer K and one set of rings only is split. The rings E' are the split rings of T-shape in cross section and adapted to be put under stress by compression or reduction 85 in their diameters, while the rings D' are solid and do not yield, the elasticity thus being confined to the rings E'.

Both sets of rings in Fig. 7 are split rings and they are of corresponding shape in cross 90 section, the set D' being adapted to be expanded and the set E' to be compressed by draft or buffing strains acting thereon through the inclined friction surface forming the contacting faces of the rings. 95

Split cylinder friction casings K' and K'' are arranged outside and inside of the split rings in position to be expanded and compressed by the expansion and compression of the rings. The heads or followers H' have 100 annular projections h' entering between the split cylindrical casings and having inclined faces for contracting with the inclines of the rings.

In some instances it may be desirable to 105 form the rings in pairs, the rings of each pair operating upon each other to produce lateral expansion or contraction of the rings, and to provide friction faces between the pair which will be operative to create friction when such 110 expansion or contraction takes place, but without any tendency to cause such movements.

In Figs. 8 and 9 the cross sectional shape of the rings is so modified as to effect this end 115 as well as to secure increased strength by an advantageous disposition of the material in the rings. The pairs of rings are indicated by the letter D'' E'' in Fig. 8, said rings having annular inclined contacting or co-operating 120 faces as before described, and substantially parallel side faces d'' e''. The faces d'' e'' extend in planes at right angles to the line of draft and buffing strains and consequently 125 do not tend to deflect the rings, but transverse movement of either ring of a pair will cause said faces to slide one upon the other and produce friction in proportion to the pressure forcing said faces into contact.

Fig. 9 shows a construction wherein the 130

same conditions exist, only in this instance the rings are strengthened and protected by annular flanges d^9 e^9 . The flanges d^9 and e^9 as well as the flanges of those rings which are 5 of T-shape serve as stops for limiting the expansion and contraction of the rings and by proper proportioning the parts may be driven down solid without extending the elastic limit of the metal.

- 10 The cylindrical casing which incloses the rings and springs is preferably relied upon to form the stop for limiting the compressive movement, and this is true whether the said casing be a solid or split cylindrical casing, for by leaving only the desired play between the ends of said casing and the followers or heads the latter will seat solidly under excessive pressure.

Obviously, the range of movement and 20 elasticity may be varied by increasing or reducing the number or varying the size or cross sectional shape of the rings, as well as by varying the angle of the annular inclined faces, or the resistance may be made differential by varying the angle of the faces, for instance, during the initial movement 25 the faces may be sharply inclined and as the movement progresses the portions of the faces coming into contact are less and less inclined. This is well illustrated at M in Fig. 3.

The central spring F in addition to augmenting the resistance of the friction rings, insures the return of the heads and followers to normal position, thereby relieving all 35 stress on the rings and preventing sticking even though the angle of the inclines should closely approach the angle of repose.

From the foregoing it will be seen that the 40 rings are put under stress by movement imparted through the contracting inclined frictional faces. Frictional resistance to the movement of the faces upon each other is very great and is occasioned not alone by the relative radial movement, but owing to the 45 fact that the splits in the rings are out of alinement or oppositely disposed there is also a rotative movement of the faces with respect to each other throughout practically the entire circumference. With such construction, the resilient elements themselves 50 become the friction elements thus avoiding the use of separate resilient and friction elements but securing the advantages of both. The area of the surface making frictional contact is very large in proportion to the range 55 of movement of any one ring, but the combined movement is very considerable, thus the heat caused by the friction is well distributed and the danger of sticking and wear- 60 ing is reduced to a minimum.

What I claim as new and desire to secure by Letters Patent, is

1. In an apparatus for the purpose specified, the combination with the series of inde-

pendent elements resilient transversely of 65 the line of pressure to be resisted and having inclined coöperating friction faces, of a resilient casing with which said elements co-operate when put under elastic stress; substantially as described.

2. In an apparatus for the purpose specified, the combination with the series of independent elements resilient transversely of 70 the line of pressure to be resisted and having inclined coöperating friction faces, of a split 75 cylindrical casing with which said elements co-operate when put under elastic stress through the coöperation of the friction faces; substantially as described.

3. In an apparatus for the purpose specified, the combination with the series of independent elements resilient transversely of 80 the line of pressure to be resisted and having inclined coöperating friction faces, of a duality of split cylindrical casings, one within 85 the other and in frictional engagement with each other and with the resilient elements, whereby pressure acting through the inclined friction faces puts the elements and casings under elastic stress; substantially as de- 90 scribed.

4. In an apparatus for the purpose specified, a resilient element of substantially T-shape in cross section with an inclined friction face on the shank portion; substantially 95 as described.

5. In an apparatus for the purpose specified, an annular resilient element of substantially T-shape in cross section with an inclined friction face on the shank portion; 100 substantially as described.

6. In an apparatus for the purpose specified, an annular resilient element of substantially T-shape in cross section with inclined annular friction faces on opposite sides of the 105 shank portion; substantially as described.

7. In an apparatus for the purpose specified, the combination with the resilient elements having inclined friction faces through 110 which said elements are put under stress, of a spring through which pressure is transmitted to said elements; substantially as described.

8. In an apparatus for the purpose specified, the combination with the annular resilient elements having friction faces inclined both to the line of pressure and to the plane of resiliency and through which the elements are put under stress, of a spring 115 arranged in line with said elements and through which pressure is made effective on said elements; substantially as described.

9. In an apparatus for the purpose specified, the combination with the series of split rings having oppositely inclined annular 120 friction faces and the series of intermediate rings having friction faces coöperating with said first mentioned faces, of a pair of heads 125

between which said rings are confined and means for holding said rings in position; substantially as described.

10. In an apparatus for the purpose specified, the combination with the series of split rings having oppositely inclined annular friction faces and the series of intermediate rings having friction faces coöperating with said first mentioned faces, of a pair of heads 10 between which said rings are confined and a bolt for holding said heads against outward movement; substantially as described.

11. In an apparatus for the purpose specified, the combination with the series of split 15 rings having inclined annular friction faces and the series of intermediate rings having friction faces coöperating with said first mentioned faces, of a pair of heads between which

said rings are confined and a central spring for returning said heads to normal position after compression; substantially as described. 20

12. In an apparatus for the purpose specified, the combination with the series of split rings having the inclined annular friction faces and intermediate rings having friction faces coöperating with the first mentioned faces, of a spiral spring, a spacer between the rings and spring and heads between which the rings and spring are confined; substantially as described. 25 30
